UNITED STATES PATENT OFFICE.

DAVID LIPPY, OF MANSFIELD, OHIO.

MEAT-SAWING MACHINE.

SPECIFICATION forming part of Letters Patent No. 599,569, dated February 22, 1898.

Application filed January 11, 1897. Serial No. 618,851. (No model.)

To all whom it may concern:

Be it known that I, DAVID LIPPY, a citizen of the United States, residing at Mansfield, in the county of Richland and State of Ohio, have 5 invented certain new and useful Improvements in Meat-Sawing Machines; and I do declare the following to be a full, clear, and exact description of the invention, such as will enable others skilled in the art to which it applies 10 to make and use the same, reference being had to the accompanying drawings, and to the letters of reference marked thereon, which form a part of this specification.

My invention relates to improvements in 15 meat-sawing machines; and the objects of my invention are, first, to construct a machine for sawing meat with a circular saw and to obviate the necessity of using a knife and saw, which are now in common use in all butchering establishments; second, to rotate a circular saw by a combination of pulleys and belts to be used in slicing meat; third, to construct the top of the table so that it can be rotated at the will of the operator; also, to 20 divide the top into separate platforms, each part provided with rollers, ratchet mechanism for operating the rollers, and a clamping device for holding the meat in position, each platform can be used for different kinds of meat; fourth, to make a cheap, durable, and 25 efficient means for the purpose stated. I attain these objects by the mechanism illustrated in the accompanying drawings.

This application is one of a series filed by 30 me of even date herewith for improvements in meat-sawing machines and bearing, respectively, the Serial Nos. 618,852 and 618,853.

Figure 1 is a side elevation of my improved meat-sawing machine, showing the general 35 construction of all the parts embodying my invention. Fig. 2 is a top view of same, showing more fully the circular platform, the rollers in each division of the same, the clamping device, ratchet mechanism, and combination 40 of pulleys and belts composing the motor. Fig. 3 is a transverse sectional view of circular platform, the mode of pivoting the same in the top of the machine-frame, and the antifriction-rollers, upon which rests the 45 platform. Fig. 4 is a front view of hand-lever, showing its general construction. Fig. 5 is a side elevation showing a different mo-

tor than the one shown in Fig. 1, the saw operating on parallel guides, the guides and saw adapted to be raised vertically when not in use; Fig. 6, a top view of same. Fig. 7 is a front view of lever, showing the mode of attaching the same at its lower end to the frame-sill. I have shown this device as a modification of Fig. 1.

Similar letters refer to similar parts throughout the several views.

In the accompanying drawings, A indicates the frame of the machine, which is composed of the legs B B, upper rails C, top D, and sills 65 E. These constitute the frame of the machine.

F indicates the circular platform; G, the metal pivot-pin, which is secured in the center and upon the under side of the platform. A suitable boxing H is placed in the top D 70 and in which is pivoted the platform F. The said platform is provided with the metal angle-irons I, so arranged upon the platform that they form recesses J. Each recess is provided with the rollers K, K', and K''. Each 75 roller is journaled in bearings made in the edge of the angle-irons to hold them in position. The roller K' is provided upon one end with a ratchet-wheel L, lever N' provided with the pawl N to manipulate the roller. 80 The clamping device is composed of the L-shaped bar O, hinged upon its lower end to the angle-iron I. The under side of the horizontal arm is provided with pointed projections P. The vertical lever Q is also hinged 85 at its lower end to the angle-iron I upon the opposite side of the platform and is provided with notches R to engage the bar O. Each set of rollers is provided with the clamping device and ratchet mechanism. This description is fully shown in Figs. 1, 2, and 3.

The locking device to hold the platform from rotating is composed of the lever S, placed under the top of the frame and in a line with the center of the circular platform. 95 One end is hinged to the side rail D of the frame A, the loose end of the lever passing through the rail upon the opposite side of the frame. An upwardly-projecting pin T is secured in the edge of the said lever, the said 100 pin passing through a hole made in the top of the table and engaging the under side of the circular platform. The platform rests upon antifriction-rollers U, secured in the top

of the frame. Upon one side of the frame and near the end is bolted the standard V. A suitable box-bearing W is cast in the same and in which is placed a suitable shaft X. 5 Upon the said shaft are secured the pulley Y and balance-wheel Z, provided with the handle B'.

C' indicates a bifurcated lever. The lower ends are pivoted upon the shaft D', the said 10 shaft having a bearing in the boxing E', secured upon the outwardly-projecting end of the sill E.

F' is a pulley secured upon the shaft D' between the box and one arm of the lever. There 15 is also a pulley G' secured upon the said shaft upon the outside of the lever. Two pulleys H' and I' are secured upon the shaft J', the said shaft journaled in each bar forming the bifurcated lever and near the upper end of 20 the same.

K² indicates round metal guide-rods. The said rods are placed in suitable bearings formed in the top of the standard V. One end of each is secured in the plates L' L', located on 25 each side of the lever. The inner ends are secured in the cross-head M'. The said cross-head is bifurcated and is provided with a saw N², saw-mandrel O', and pulley P'. The pulley is placed within the bifurcation formed in 30 the cross-head.

When the lever C' is placed in position, the pulleys Y and G' are in line and provided with a belt Q'. The pulleys F' and I' are also in line; also, the pulleys P' and H'. Each pair of pulleys is provided with suitable belts R' 35 and S' to connect the same.

It will be readily seen by those skilled in the art that when the operator takes hold of the handle B' and rotates the wheel Z motion 40 is conveyed to the shaft and pulleys D', F', and G' through the belt Q'. It is also conveyed to the pulleys H' and I' through the belt R' and to the saw N' through the belt S'.

When the operator wishes to cut meat, he 45 places a joint upon one set of the rollers and then feeds it forward by the ratchet mechanism until a sufficient quantity of the meat projects past the saw. It is then held firmly by the clamp-levers O and Q. He then rotates the 50 saw by the mechanism described and then forces the saw through the meat and bone by the lever C'. As soon as the operator releases the lever it returns to its normal position by the action of the spring T'. This description 55 is fully illustrated in the sheet of drawings marked Plate 1.

The sheet of drawings marked Plate 2 is shown as a modification of Fig. 1, Plate 1, the frame and platform being the same as described. The particular change is in the cross-head and guides and mode of belting. Where three are used in the description given above, two only are used in this device. The cross-head A² is placed upon the two parallel guides B². The inner ends are pivoted upon each side of the standard C². One of the guides

is provided with a vertical lever D², having a spring-bolt fastener E², which engages in suitable notches formed in the top of the standard C². 70

F² indicates connecting-rods, the outer ends secured in lugs formed upon the top of the cross-head, the inner ends to the lever G².

H² indicates a foot or support secured upon the outer ends of the guide-rods, and when 75 in position, as shown, the foot rests upon the top of the table I² to hold the guide-rods parallel with the top of the frame A².

J² indicates a belt which passes around the mandrel-pulley K², thence over the pulley L², 80 then downward around the pulley N², up over the pulley M², forming a communication from one to the other. By pulling downward upon the lever D² the guides, foot, and saw are raised in a vertical position to allow the operator to place meat upon the platform. 85

Having fully described my invention, what I claim as new, and desire to secure by Letters Patent, is—

1. The combination of a frame, a revolute 90 platform divided in parts, a set of rollers mounted upon each part, a separate clamping device and ratchet mechanism for each set of rollers, and a revolute saw.

2. The combination of a frame, a revolute 95 platform, divided into parts mounted thereon, a set of rollers mounted upon each part, a clamping device for each set of rollers, a revolute saw, and mechanism for revolving the saw and feeding it toward the part of the platform containing the meat to be sawed.

3. The combination of a frame, a revolute platform, divided into parts mounted thereon, antifriction-rollers between said platform and frame, a locking mechanism for locking the 105 platform in a rigid position while in operation, a set of rollers mounted upon each part, a clamping device and ratchet mechanism for each set of rollers, and a revolute saw.

4. The combination of a frame, a revolute 110 platform divided into parts mounted thereon, means to hold the same in a rigid position, a set of rollers mounted in each part, a clamping device and ratchet mechanism for each set of rollers, a circular saw journaled in a reciprocating cross-head, a hand-motor for operating the saw, the same consisting of a driving-shaft journaled in a bearing on one side of the frame, a pulley and balance-wheel carried by the shaft, a bifurcated lever journaled 115 at its lower end on a shaft located in a boxing on the sill of the frame, two pulleys journaled on a shaft located between the bifurcated arms of the lever near the upper end thereof, two pulleys journaled on the shaft on which the lower end of the bifurcated lever to the pulleys on the power-shaft and knife-carrying shaft respectively; whereby power is conveyed to the knife for operating the same. 120

5. The combination of a frame, a revolute 125 platform divided into parts, a set of rollers mounted upon each part, a separate clamping

device and ratchet mechanism for each set of rollers, a circular saw mounted on a shaft journaled in a cross-head, two rods loosely mounted in a bracket located on the upper 5 part of the frame, the forward ends of the rods attached to the cross-head and the rear ends attached to a bifurcated lever whereby the circular saw is reciprocated to engage the

meat to be sawed or disengaged therefrom, and means for revolving the saw. ¹⁰

In testimony whereof I affix my signature in presence of two witnesses.

DAVID LIPPY.
